APPARATUS FOR WINDING A COIL ASSEMBLY
Mario Sciaky, Saint Cloud, France, assignor to Welding
Research, Inc., Chicago, Ill., a corporation of Illinois
Filed Nov. 3, 1961, Ser. No. 150,022
2 Claims. (Cl. 242—9)

The invention relates to an apparatus for winding sheet metal around a tube in order to form a magnetic circuit for transformers and the like. More particularly the invention has for its object the winding of sheet metal in a manner to produce coil assemblies with wound magnetic cores in one operation, whereas in known methods at least five successive operations have been required.

The winding of magnetic cores by coiling a strip of sheet metal around a mandrel has been in use and is well known. However, in these methods the mounting of the wire coils is possible only after the magnetic circuit had been constructed. In spite of many complications the technique has been perfected and does not offer any particular difficulty.

It may also be observed that the method of winding magnetic cores from sheet metal strip can be preformed in a convenient manner and thus the method is more advantageous than that which consisted in cutting the sheet metal and assembling the cut strips by interleaving. If annealing of grain-oriented sheet metal is indispensable, it is not necessary for silicon sheet metal. However, it has been required up to the present time to maintain this operation in order to eliminate the stress on the sheet metal which has a tendency to open the magnetic circuit. It is therefore seen that with the methods as heretofore employed, the following operations were necessary. Winding of the magnetic cores on a mandrel; annealing; varnishing; cutting; mounting the wire coils on the transformer and attaching the same by means of clamping rings.

The purpose of the present invention is to eliminate the inconveniences by eliminating a large number of the operations although still obtaining a high-quality product.

Another object of the invention is to provide apparatus for producing coil assemblies with wound magnetic cores and wherein said apparatus produces rotation of the tube which is mounted on the sides of the coils that receive the wound magnetic circuit, the sheet metal strip being secured to the tube for winding thereon and which remains fixed with respect to the coils.

A more specific object of the invention is to provide apparatus for winding relatively thin sheet metal or wire around coil assemblies, said apparatus incorporating means for displacing the sheet metal or wire axially during its winding in order to obtain a helical winding.

The machines to wind sheet metal around coil assemblies according to the invention are shown as examples on the attached drawings in which:

FIGURE 1 shows a coil assembly with two wound magnetic circuits according to the method of the invention;

FIGURE 2 represents the method of winding of the sheet metal around one of the sides of the coil;

FIGURE 3 represents schematically the machine to obtain wound magnetic circuits according to the method of the invention;

FIGURES 4 and 5 represent schematically a second method employing a driving device for rotating the tube mounted around the coils which receive the wound magnetic circuit; and

FIGURE 6 represents the machine used to coil the magnetic circuit according to the method described in FIGURES 1, 2 and 3, and completed by a device which produces a helical winding of the sheet metal or wire.

According to the method of the invention, the sheet

2

metal which forms the magnetic circuit is wound directly on the coil assembly such as the coils of a transformer, and the sheet metal is terminated by means of a few spot welds.

5 To simplify the description, one assumes as an example that the coil assembly 1 of the transformer has been molded and the two coil elements which will be inside the magnetic circuit have the form of a cylinder 4, see FIGURE 1.

10 Part 1 shown in full line on FIGURE 1 contains the primary and secondary coils encased in resin in order to obtain a compact unit which does not necessitate a device to maintain in place the elements of the transformer. The primary connections are at 2 and the secondary connections are at 3. The sheet metal of the magnetic circuit shown in dotted lines at 5 and 6 must be wound around columns 4.

15 According to the method of the invention, see FIGURE 2, around each column 4 is mounted a tube 7 which consists of two half cylinders made of 2 or 3 mm. thick sheet metal.

20 In one of them is welded the edge of the sheet metal strip to be wound. The tube 7 is then made to rotate and the sheet metal is wound around the tube. When the desired winding diameter is reached, it is sufficient to terminate the sheet metal with a few spot welds and to cut the strip. The metal tube 7 remains in place on the column 4 and becomes part of the core structure.

25 The above method presents several advantages particularly a reduction to one operation of the five operations which are necessary in the known processes described above. Particularly, the cutting is eliminated, which in spite of all precautions may short circuit the neighboring laminations and increase the eddy current losses.

30 FIGURES 2 and 3 represent a machine which will operate to perform the above method. In FIGURE 2 one of the magnetic circuits 5 has been shown in full line wound around column 4 of the coil assembly 1 and the second magnetic circuit 6 which will be wound later is shown in dotted lines. On each end of tube 7 surrounding column 4 are mounted wheels 8 and 9 which are cut along a diameter and which are assembled by an appropriate device. Each wheel contains a smooth rim 15 and gear teeth 16. The two wheels roll on three rollers 10₁, 10₂ and 10₃ which contain a throat 17 which centers the part and gear teeth 18 through which the part is driven.

35 FIGURE 3 shows a cross section of the profile of the machine. Sheet metal 11 passes through three rollers 12, 13 and 14, arranged in a manner which pre-forms the sheet metal and simplifies its winding. One of the wheels 50 9 is also shown rolling on the three rollers 10₁, 10₂ and 10₃, as well as cylinder 7. The second magnetic circuit 6 is also obtained in the same manner.

40 In order to make the drawing of FIGURE 2 readable, a certain distance was provided between the magnetic circuit 5 and the end of the coil assembly 1. In practice, this distance will be reduced as much as possible by using wheels 8 and 9 as narrow as can be produced. Various modifications can be made to the above described machine without going out of the range of the invention.

45 FIGURES 4 and 5 represent another modification of a device which rotates the tube 7, which is mounted around the coils which receive the wound magnetic circuit. Tube 7 is supported by several lines of rollers 20 which are rubber covered for example, to obtain a large coefficient of adherence. On FIGURES 4 and 5, four lines of rollers 20 are shown. At least one of these rollers is a motor. According to the results that one wishes to obtain, the speeds of the other rollers which are driven could be established at a desirable ratio. Each line of rollers 20 is supported by an arm 21 which pivots on a support 22. The arms 21 of each line of rollers are coupled to each other by coupling rods 23 so that the

center of rotation of the assembly remains fixed. Piston 25 which slides in an air-compressed cylinder 24 is coupled to one of the levers 21 by the rod 26 in order that the rollers are pressed under air on the sheet metal 11 which is wound around tube 7.

Another way to realize this machine is shown in FIGURE 6. This machine can produce a magnetic circuit with a strip of small width or with wire. This may be necessary for various reasons and particularly when the transformer will operate at high frequency. This machine is shown schematically on FIGURE 6 and to simplify its description, the front part of the coil assembly 1 has been removed. This machine, similar to that described previously in FIGURE 3, contains in addition a moving roller 32 which guides the narrow strip 30 in order to obtain a helical winding. This roller, whose throats are at a distance equal to the width of the strip, rotates freely on axle 33 but does not slide on this axle.

Axle 33 goes through two supports 31 and 34 which guide this axle. The support 31 contains a mechanism which insures the axial displacement of axle 33. This translation movement can be adjusted in order to obtain a winding pitch equal to the width of the strip. The drive of the control device of the support 31 is joined to the rotation movement of the wheels 10. Although the diameter of the magnetic circuit 5 increases progressively, the pitch remains constant and it is sufficient that the displacement of axle 33 be joined in a constant ratio with the rotation of wheel 9. This ratio is such that one revolution of the wheel 9 causes a displacement of axle 33 equal to the width of the strip.

The support 31 also contains a system which reverses the direction of displacement of axle 33 when the strip 30 has been displaced until it reaches one of the gears 8 or 9. It is evident that the invention is not limited to the examples described and represented above from which other forms of realization can be obtained without going outside the range of the invention.

What is claimed is:

1. In apparatus for winding a strip of sheet metal around the cylindrical part of a coil assembly, whereby to form a metal core for the assembly, in combination, a metal tube having a concentric encircling relation with the cylindrical part, said metal tube consisting of two longitudinal half sections, whereby to facilitate the placing of the tube around the cylindrical part of the coil assembly, one end of said sheet metal strip being secured to one of the half sections of the tube, at least one gear wheel releasably fixed to an end of the tube, and driving means for rotating the tube including a pinion gear having meshing relation with the gear wheel.

2. Apparatus for winding a strip of sheet metal around the cylindrical part of a coil assembly as defined by claim 1, wherein the gear wheel is sectional along a diameter to permit the fixing of the gear wheel to an end of the tube in concentric relation therewith and its subsequent release from said tube.
